UNITED STATES PATENT OFFICE.

JOHN R. TOBIN, OF LANGFORD, SOUTH DAKOTA.

RAPID-FIRE TOY CANNON.

1,223,448.

Specification of Letters Patent. Patented Apr. 24, 1917.

Application filed October 18, 1916. Serial No. 126,349.

To all whom it may concern:

Be it known that I, JOHN R. TOBIN, a citizen of the United States, residing at Langford, in the county of Marshall, State 5 of South Dakota, have invented certain new and useful Improvements in Rapid - Fire Toy Cannon; and I do hereby declare the following to be a full, clear, and exact description of the invention, such as will enable others skilled in the art to which it 10 appertains to make and use the same.

This invention relates to toy cannons and has special reference to a rapid fire toy cannon arranged to discharge a large number 15 of bullets in a short time.

One important object of the invention is to improve and simplify the general construction of devices of this character.

A second important object of the invention 20 is to provide a toy cannon of this character with a magazine capable of being placed in or moved out of communication with the barrel of the gun so that the gun may be used as a single shot or repeating 25 cannon.

A third important object of the invention 30 is the provision of an improved arrangement of toy cannon mounted to swivel on a stand, the barrel of the gun having the operating mechanism connected directly thereto so that the swiveling movement does not interfere with the firing of the cannon.

With the above and other objects in view, as will be hereinafter apparent the invention 35 consists in general of certain novel details of construction and combinations of parts hereinafter fully described, illustrated in the accompanying drawings, and specifically claimed.

40 In the accompanying drawing, like characters of reference indicate like parts in the several views, and:—

Figure 1 is a side elevation of a toy cannon constructed in accordance with this invention;

Fig. 2 is a plan view thereof;

Fig. 3 is a longitudinal section on the line 3—3 of Fig. 2 with the parts in firing position;

50 Fig. 4 is a section on the line 4—4 of Fig. 1 with the magazine in communication with the barrel;

Fig. 5 is a section similar to Fig. 4 but showing the magazine moved into cut off 55 position;

Fig. 6 is a detail section on the line 6—6 of Fig. 1;

Fig. 7 is a detail plan view of the frame;

Fig. 8 is a detail front elevation thereof.

In the embodiment of the invention herein 60 illustrated there is provided a base 10 whereon is mounted a standard 11 having feet 12 suitably secured to the base. On top of this base is swiveled the breech 13 of a barrel 14 which may thus swing in a horizontal plane. This barrel 14 is provided with a suitable opening 15 formed in its lateral wall and surrounding the barrel and revoluble thereon is a collar 16 having a similar opening therein registering with the 65 opening 15 and to this collar is connected a magazine 17 registering with the opening in the collar. These openings are so arranged that when the magazine is elevated at an angle bullets held in the magazine will feed 70 downwardly into the barrel 14. When, however, the magazine is turned to a substantially horizontal position the openings will be sufficiently out of registry to prevent the feeding of said bullets. Normally the magazine 75 is closed by a cap 18 which may be removed for the purpose of loading said magazine.

Reciprocably mounted in the barrel 14 is a plunger 19 which, in its forward position, 80 closes the opening to the magazine while when retracted the forward end of the plunger 19 lies behind the opening to the magazine so that bullets may pass down from said magazine into the barrel, it being observed that but one bullet is fed at a time, owing to their size. Connected to the plunger 19 and to the forward end of the barrel 14 is a spring 20, the connection being 85 through the medium of a cross arm 21 carried by the rear end of the plunger and having its upper end projecting vertically upward while its lower end projects downward and is provided with a head 22. Fixed to the breech portion 13 of the barrel are downwardly extending arms 23 and forward of the breech portion are other downwardly extending arms 24 which are connected at their lower ends to the rearwardly extending guides 25 which receive the head 22 so that 90 the arm 21 is at all times held vertical. Furthermore it will be observed that by means of this construction the swinging of the barrel will also swing the guide 25.

Extending diagonally upward and rear- 110

wardly from the lower ends of the arms 24 and connected to the breech portion 13 are other arms 26 wherein is journaled the crank 27 which alternately engages with and disengages from the upwardly extending portion of the arm 21 as said crank is rotated thus effecting retraction and release of the plunger 19. By means of this the plunger is drawn backward and then released so that 10 the spring pulls the plunger quickly forward and forces the bullet out of the forward end of the barrel.

Moreover, the guide 25, in its swinging movement traverses a bar 28 having an upward projection 29 in each end so that by 15 this means the barrel is both steadied and limited in its swinging movement.

In the operation of the device the cap 18 is removed and the magazine loaded with as 20 many bullets as desired. If it be desired to fire but a single shot from the cannon the magazine is raised to communicating position and the plunger 19 retracted, care being taken not to move the crank far enough to 25 release said plunger. A bullet will then drop out of the magazine into the barrel of the gun or cannon. The crank is then moved farther forward until the plunger is released whereupon the bullet is ejected from 30 the muzzle of the barrel. If the magazine be now turned downward the plunger may be retracted without reloading but, on the contrary, if the magazine be left standing in its communicating position repeated turnings 35 of the crank will cause repeated ejections of the bullets so that by rapidly turning the crank a rapid succession of bullets may be ejected.

There has thus been provided a simple and 40 efficient device of the kind described and for the purpose specified.

It is obvious that many minor changes may be made in the form and construction of the invention without departing from the material principles thereof. It is not therefore 45 desired to confine the invention to the exact form herein shown and described but it is

wished to include all such as properly come within the scope claimed.

Having thus described the invention, what 50 is claimed as new, is:—

1. In a toy cannon, a stand, a barrel swiveled on said stand for swinging movement in a horizontal plane, a firing plunger reciprocal in said barrel, a spring connected 55 to the plunger and barrel and urging said plunger forward, arms fixed to said barrel and extending downwardly therefrom, a guide carried by said arms and extending rearwardly therefrom, a cross arm carried 60 by said plunger and having its lower end received in said guide and its upper end projecting above the barrel, other arms fixed to the barrel and extending rearwardly and upwardly therefrom, and a handled crank 65 journaled in the last-mentioned arms and alternately engaging and releasing the upper end of said cross arm.

2. In a toy cannon, a stand, a barrel swiveled on said stand for swinging movement in 70 a horizontal plane, a firing plunger reciprocal in said barrel, a spring connected to the plunger and barrel and urging said plunger forward, arms fixed to said barrel and extending downwardly therefrom, a guide 75 carried by said arms and extending rearwardly therefrom, a cross arm carried by said plunger and having its lower end received in said guide and its upper end projecting above the barrel, other arms fixed to 80 the barrel and extending rearwardly and upwardly therefrom, a handled crank journaled in the last-mentioned arms and alternately engaging and releasing the upper end of said cross arm, and means engaging said 85 guide and limiting the swinging movement of the guide and barrel.

In testimony whereof, I affix my signature, in the presence of two witnesses.

JOHN R. TOBIN.
